No. 894,988.

PATENTED AUG. 4, 1908.

R. STREICH.
ADVERTISING DEVICE.
APPLICATION FILED JULY 17, 1907.

UNITED STATES PATENT OFFICE.

ROBERT STREICH, OF CHICAGO, ILLINOIS.

ADVERTISING DEVICE.

No. 894,988.

Specification of Letters Patent.

Patented Aug. 4, 1908.

Application filed July 17, 1907. Serial No. 384,168.

To all whom it may concern:

Be it known that I, ROBERT STREICH, a citizen of the United States of America, and resident of Chicago, Illinois, have invented a 5 certain new and useful Improvement in Advertising Devices, of which the following is a specification.

My invention relates to improvements in advertising devices, and has for its object the 10 production of a device by the use of which glasses filled with a champagne-colored liquid may be made to simulate the appearance of fresh champagne.

A further object is the production of a device by means of which a series of small globules may be caused to rise through the liquid.

A further object is the production of a device by means of which a series of air or gas globules may be caused to rise through the 20 liquid.

A further object is the production of a device that will be constant in its operation and can be cheaply constructed and operated.

These and such other objects as may hereinafter appear, are attained by my device, an embodiment of which is illustrated in the accompanying drawings, in which

Figure 1 represents a plan view of my device, set up and ready for operation. Fig. 2 25 is an enlarged detail showing the tube between the tank and display stand.

Like numerals of reference indicate like parts in the several figures of the drawing.

Referring by numeral to the accompanying drawings, 3 represents a tank of compressed air or gas; 4 a pump by means of which the pressure in the tank may be regulated; 5, a gage; 6, a valve adjacent to said tank; 7, a connection; 8, a second valve interposed between the connection and the display stand; 9, a tube or connection extending from said valve. This tube extends underneath a display table or shelf 10 provided with one or more openings 11. The upper 40 end of the tube 12, provided with an enlarged portion or bulb 13, extends upwardly through the opening 11, and connects at its lower end with the tube or connection 9. This tube 12 preferably terminates at its 45 lower end in a restricted opening 14. A base or shelf 15 serves to prevent the end of the tube 9 from becoming easily disengaged from the end of the tube 12. Seated on the display table or stand above the opening 11 is a 55 glass receptacle, preferably a champagne glass, 16, provided with an air opening 17

extending from the bottom of the stem 18 through the base 19, and registering with the opening 11 of the table. This opening 17 is preferably enlarged at the bottom, and a 60 rubber or cork collar or washer 20 is inserted. The upper portion of the tube 12 extends upwardly into said collar.

In order to prevent the fluid in the glass from leaking downwardly into the tube 9 65 when the pressure is shut off, I insert cellulose or some like fibrous material in the lower end of the tube 12, as shown at 21 in Fig. 2. It is understood that I may have as many glasses on the table 10 as desired, each one 70 being connected independently with the tank 3. The receptacles or glasses 16 being filled with old champagne, wine, or clear or colored liquid, and the gage 5 indicating the requisite pressure, the valves 6 and 8 are opened and 75 the compressed air, carbonic acid gas or other gas used forced through the tubes, the pressure is turned on before the fluid is allowed to reach the bottom of the tube 12, and the gas forces itself through the restricted opening 14, which is so regulated in size that as the gas presses through the opening the weight of the surrounding liquid in the tube disintegrates it, as it were, into minute globules or bubbles which rise into the bulb 13, 80 through the upper end of the tube 12 into the stem of the glass, and thence upwardly into the body thereof. The cellulose in addition to preventing the leakage of the fluid, serves to further break up the upward current of 90 air or gas, with the result that a large number of small globules are thrown into the interior of the chamber 22. The upward pressure being greatest directly over the opening, the globules tend to take a diagonal direction 95 toward the side of the bulb, thence upwardly, following the line of the side. I find that when the pressure is regulated so as to give the best results, that the line of direction of most of the globules is past the upper 100 opening into the tube, and in the direction indicated by the arrows in Fig. 2, thence upwardly through the tube into the stem or glass.

In the event that the tank is located close 105 to the table, one of the valves 6 or 8 may be dispensed with, as perfect control may be obtained with a single valve. But when, as is frequently the case, it is necessary to have the supply tank at a considerable distance 110 from the table, the two valves are necessary, the first adjustment being made at the tank

by means of the valve 6, generally consisting in opening the valve to its fullest extent, so that the air or gas may pass upwardly as far as the valve 8, which is preferably located close to the display table. Then, with the entire display portion of portion of the apparatus in full view of the operator, the valve 8 is regulated so as to attain the most satisfactory results without the necessity of further disturbing the valve 6. Where the display is made in a show window on top of a shelf or stand or step, no particular arrangement of parts is needed; but where the display is made on a table in a window, or in any isolated position, greater care is necessary, the tube or tubes being brought up preferably inside of a center leg, the table being covered with cloth, preferably black velvet, in which small openings have been made to permit the insertion of the tubes. With a number of glasses in position arranged about the table, and the pressure properly adjusted, the effect is strikingly realistic, and the simulation of fresh champagne is so perfect that if an empty glass is placed among the display glasses and then filled with fresh champagne, it is impossible to detect any difference between the effervescence in the glasses. This experiment has been tried many times, and it is only possible to know the difference after the champagne in the disconnected glass has become stale.

Colored fluids and colored glasses may be

used with striking effect if desired, or various chemicals may be used in the glasses, giving unique effects, but all of these effects are contemplated by me in the use of this device.

I claim:

1. An advertising device consisting of a display stand, a receptacle containing liquid, a compressed air or gas supply in communication therewith, and means located between said receptacle and supply for producing an effervescent effect in said liquid, said means comprising a tube partially filled with fibrous material, said tube being provided with an enlargement in communication with said liquid.
2. In an advertising device, consisting in a display stand, a long stemmed glass receptacle seated therein and provided with an opening through its base and stem, a tube having a bulb in its upper portion connecting with said receptacle, cellulose compressed in the lower portion of said tube, a compressed air or gas tank in communication with said tube, and valves for regulating the flow of the contents of said tank, whereby an effervescent effect may be produced in said glass receptacle.

Signed by me at Chicago, Illinois, this 29th day of April, 1907.

ROBERT STREICH.

Witnesses:

SARAH LEWIS,
ALBERT JOHN SAUSER.
